UNITED STATES PATENT OFFICE.

ALBERT E. HALL AND MILAN W. HALL, OF PLAINFIELD, NEW JERSEY.

PUMPING-ENGINE.

SPECIFICATION forming part of Letters Patent No. 289,648, dated December 4, 1883.

Application filed September 3, 1883. (No model.)

To all whom it may concern:

Be it known that we, ALBERT E. HALL and MILAN W. HALL, both citizens of the United States, and residents of Plainfield, Union county, New Jersey, have invented certain Improvements in Direct-Acting Pumping-Engines, of which the following is a specification.

Our invention relates to that class of pumping-engines wherein twin engines, the piston-rods of which are connected directly to the pump-pistons, are employed. The valves are balanced, and the valves of one engine control the parts of the adjacent engine. The stroke of the valve is coincident with that of the piston of the engine which actuates it.

Our invention consists, chiefly, in the construction of the valve-ports and port-passages and their relative connection and arrangement, whereby each engine so controls the movements of the other that each piston commences to move only when the other has nearly reached the end of its stroke; and when each piston completes its stroke it stops and remains stationary during nearly the entire stroke of the other, and until started back by the other. This long pause of the pistons allows the water-valves of the pump ample time to seat themselves before the return-stroke commences. This relative movement has been before obtained in duplex steam-pumps, but only in those having tappet-valves, where the valve remains stationary while the piston which operates it is moving, and until the latter reaches almost the end of its stroke, when it suddenly shifts the valve. In our pump each valve moves all the time that its actuating-piston is moving, and with a speed directly proportioned to the speed thereof. We believe we are the first to accomplish this result of securing an alternate action of the pistons, with a long pause for each at the end of its stroke, in an engine wherein the valves move with their actuating-pistons and the valve of each cylinder is operated by the piston in the other cylinder. In this way we have availed ourselves of the special advantages of both types of pumping-engines, and have thus been enabled to construct an engine superior to either.

Our invention also consists in the relative arrangement of the steam ports and passages in an engine of the character described, where-

by when the engine is running the inlet-ports are always open, and the movements of the pistons are controlled wholly by the opening and closing of the exhaust.

In the drawings which serve to illustrate our invention, Figure 1 is an end view of the engines and their steam-chests, showing the outer cylinder-heads removed. Fig. 2 is a plan of the engines with the steam-chests removed, so as to show the ports. The port-passages in Figs. 1 and 2 are indicated by dotted lines. Fig. 3 is a vertical mid-section taken in the axis of one of the engines on line 3 3 in Figs. 1 and 2. Fig. 4 is a plan of a detached steam-chest as to the left half and a horizontal section as to the right half, the section being taken on line 4 4 in Fig. 5. Fig. 5 is a cross-section taken on line 5 5 in Fig. 4.

A A' are the cylinders of the two engines, cast in one piece, with the various port-passages cored out in the tie-piece which connects them.

B B' are the pistons, and C C' the piston-rods.

D is a part of one of the pumps. (Shown only in Fig. 3.) These pumps may be of the usual construction.

E E' are the steam-chests. A description of one of these will serve for both. Through the chest is formed a cylindrical bore, one end of which may be closed by a screw-plug, a, while the other end is closed by a stuffing-box, b.

F F is the valve, which comprises two pistons mounted on a stem, c. The steam-inlet or receiving-port in cylinder A and its chest is lettered d, and that in cylinder A' and its chest d'. These connect by a cross-passage, e, (see Fig. 1,) and with the steam-supply pipe at G. (See Fig. 2.) The pistons of the valves never entirely close the ports d and d', and the spaces between said pistons in the chests are always open to the live steam. The live steam is never cut off from the cylinders by the valves, and as the steam enters between the two pistons of the valve the latter is perfectly balanced. In the roof of the steam-chest are the exhaust-ports g g, which connect by a passage, h, in the roof with a passage, i, Fig. 2, which leads to the main exhaust-outlet H. A similar port-passage, h', leads the exhaust-steam from the other steam-chest to H. Thus

the exhaust port and passages in each case lead to a common outlet, H.

It will be seen by reference to Fig. 1 that the exhaust-passage *i* is arranged above the live-steam passage *e*, and both are or may be in the same vertical plane, *j j*, in cylinder A, and *j' j'* in cylinder A' (see Figs. 2 and 3) are the ports through which the steam passes on its way to and from the cylinders, the former connecting by crossed passages *kk* with cylinder A' and the latter by direct passages *ll* with cylinder A. These passages enter their respective cylinders at *m m* and *m' m'*, as shown in Figs. 1, 2, and 3.

15 We will now describe the operation so far as may be. We will suppose piston B to stand at the inner end of its stroke, as in the drawings, and steam is admitted at G. Live steam flows into cylinder A behind piston B, 20 and flows into A' in front of piston B', which may be at the end of its outstroke. B cannot move, but B' moves to the end of its instroke, carrying with it its valve, which is coupled directly to its piston-rod by an arm (not shown) 25 corresponding to I in Fig. 3. When the piston B' reaches the end of its instroke, it and its valve will have assumed the position of piston B and valve F shown in Fig. 3. Port *j'* in chest E' will now be open to the exhaust-outlet H, and piston B will be free to move, as its receiving side is always open to the live steam, and the movement of piston B' and its valve has opened its exhaust side to the exhaust-outlet H. Piston B' will now stand until B has made its outstroke, when the latter will, through the medium of its valve F, open the exhaust side of B' to the outlet H and allow said piston to make its outstroke. Thus the pistons move alternately, and have a long 35 rest after each stroke, giving the pump-valves ample time to seat by gravity; and each piston is controlled wholly by its exhaust—that is to say, one side of the piston is always open to the live steam, alternating at each movement, of course, and the movement is controlled by the opening of the exhaust on the opposite side. When the valve F is, at the middle of its stroke, all three ports *d j j'* will be between the two pistons of the 40 valve, and for a time both sides of the piston B' will be open to the live steam; but as the valve nears the end of its stroke one port *j* will be momentarily covered by a valve-piston, and then opened to the exhaust. Piston B' is then free and instantly moves. Piston 45 B not having moved quite to the end of its stroke, the two pistons will, for a very brief interval, move together; but B will stop at the end of its stroke, and stand until B' opens 50 it to the exhaust.

In Fig. 3 piston B is shown as standing very close to the end of the cylinder; but in practice there is a cushion of steam between it and the cylinder-head, which will ordinarily prevent it from moving up so close. Therefore 55 as the valve F moves with piston B its

rear portion will not pass quite so far beyond the port *j* (to the left) as the drawings represent. In fact, we usually make the space between the pistons of the valve equal to the 70 stroke of the engine, and arrange the ports *j* in such a position that the rear piston of the valve will uncover its port a moment before the valve reaches the end of its stroke. We thus cause one engine to set the other in motion a moment before it stops, in order to keep the column of water in motion and avoid intermittent action of the pump.

As the pistons of the valve must cross the ports *j* in the chest, we make these ports by 80 boring a series of holes, as best shown in Fig. 4. This construction prevents the packing-rings on the valve-pistons from dropping into the port and catching, as they are liable to do where the ordinary elongated port is used. 85

We will now explain the device for effecting a cushion of the piston on the exhaust-steam, in order to prevent the piston from striking the cylinder-head, referring particularly to Fig. 3 of the drawings. We provide 90 steam-cushions at each end of the stroke by setting the ports *m m m' m'*, where they open into the cylinders A' A, respectively, a little back from the cylinder-heads, so that each piston shall close the exhaust just before reaching the end of its stroke. As there is no fly-wheel to start the piston on its return-stroke, it is necessary to provide another port, *s*, closer to the cylinder-head, communicating with the steam-passage *l*, to admit steam between the 100 piston and cylinder-head to start the piston back. In order to prevent the confined cushion of steam from escaping to the exhaust through this port, a check-valve, *q*, is interposed between it and the passage *l*, as shown 105 in dotted lines in Figs. 2 and 3. This feature of our engine is reserved for the subject of a future application.

As before stated, the two engine-cylinders are cast in one piece, and each steam-chest is 110 secured to its cylinder by four bolts, *u u*, as shown.

Our engine is very simple in construction, all articulations being avoided, and it will start, no matter in what positions the pistons 115 may stand relatively to each other.

Having thus described our invention, we claim—

1. A steam pumping-engine consisting of the combination of duplex cylinders, pistons, 120 steam-chests, and valves, a suitable connection between the valve of each cylinder and the piston of the other cylinder, substantially as described, whereby the valve moves with said piston during all the time that the latter is 125 moving, and with a speed proportional to the speed of the latter, and the steam-ports in the valve-chests arranged relatively to the valves and the inlet and exhaust apertures, in substantially the manner described, whereby each 130 piston is started when the valve actuated by the other piston is near the end of its stroke,

and each piston, on reaching the end of its stroke, pauses until the other has nearly completed its stroke, as set forth.

2. A steam-engine having two cylinders, 5 two pistons and their piston-rods, and two piston-valves, the valves having a stroke equal to the piston and actuated directly thereby, and the piston in one cylinder actuating the valve which controls the exhaust of the other cylinder, the steam ports and passages being arranged substantially as described, whereby 10 when the engine is running the inlet-ports are always open, and the movements of the pistons are controlled wholly by the opening and 15 closing of the exhaust, as shown and described.

3. In a steam pumping-engine having duplex cylinders, pistons, steam-chests, and valves, the valve controlling the admission of steam to each cylinder being connected directly

to and driven by the piston of the other cylinder, the combination of the steam-chests, each provided with an inlet-port, *d*, with ports *j*; *j* connecting with the cylinder, and with exhaust-ports, with a valve, *F F*, in each steam-chest, consisting of two pistons so spaced relatively 20 to the cylinder-ports that one of the latter will be opened to the exhaust and the other to the inlet only near each extreme stroke of the valve, substantially as and to the effect set forth. 25

In witness whereof we have hereunto signed our names in the presence of two subscribing witnesses. 30
